H. M. WILLIAMSON

ELECTRICAL RECEIVER

Filed July 12, 1923

INVENTOR.
Henry M. Williamson,
BY Thomas G. Stewart.

ATTORNEY.

UNITED STATES PATENT OFFICE.

HENRY M. WILLIAMSON, OF CHICAGO, ILLINOIS, ASSIGNOR TO JOHNSON-WILLIAMSON LABORATORIES, INCORPORATED, A CORPORATION OF ILLINOIS.

ELECTRICAL RECEIVER.

Application filed July 12, 1923 Serial No. 650,981.

The invention relates to receivers which operate to translate electrical undulations into audible sound waves, one object thereof being to produce an exceedingly sensitive instrument which will propagate sound waves in a clear and distinct manner, whereby listeners will hear reproduced sounds the same as if they emanated from an original source. It is a further object of the invention to produce a loud-speaking receiver in which the vibrating element may be able to effectively vibrate, without striking other parts and thereby producing what is known as "chattering", a phenomenon which overwhelms articulate speech when the current is strong enough to produce it. Attempts have been made to eliminate this defect which is inherent in ordinary loud speakers, by providing a considerable space between the armature and the magnet, but the increase of distance between the two elements lessened the magnetic attraction in proportion to the square of the distance, and necessitated utilization of a current all out of proportion to the work performed in vibrating the armature.

The device herein described and shown, is so constructed as to prevent excessive vibrations of the armature, and to admit of the use of a small amount of electrical energy while producing a strong magnetic action to thereby compel the armature and its associated acoustical elements to operate with a high degree of efficiency.

The invention will be fully understood if reference is made to the accompanying drawing, in which—

Figure 1 is a plan view of the receiver;

Figure 2 is a view of the receiver in elevation;

Figure 3 shows a spring used in the receiver;

Figure 4 is a view of the armature;

Figure 5 is a sectional view showing the electro-magnets, the armature and the spring;

Figures 6 and 7 are views showing the needle of a phonograph applied to the armature, whereby the acoustical elements of the phonograph may be used to impart the vibrations to the air.

The new device embodies, as its principal elements, a casing 1, a permanent magnet 2 having pole-pieces 3, a spring 4 having a

notch, mounted on cross-pieces 5, an armature 6, notched on both sides, carried by said spring and extending between said pole-pieces, and two electro-magnets 7, arranged one at each end of said armature. The spring acts torsionally, and is strong enough to normally retain the armature in substantially a median position between the pole-pieces, although it allows said armature to vibrate with sufficient amplitude to produce the desired sound waves, the object, as already stated, being to prevent contact with the pole-pieces. The interlocking joint between the spring and the armature produces a rigid entity whose parts are relatively immovable.

The armature, while extending through the electro-magnets, is slightly spaced therefrom in order that it may oscillate between the pole-pieces, the said spring being determinative of its center of oscillation.

The magnet 2 and the pole-pieces 3 coincide, and the pole-pieces are, therefore, subjected to the action of maximum lines of force. Also, the ends of the spring are unadjustably fixed to the cross-pieces 5, the result being avoidance of chattering due to loosening of the parts by the rapid and strong vibrations of the armature, as heretofore experienced in the operation of other instruments. Furthermore, the continuity of the spring compels the armature to truly oscillate in a well-defined single plane, whereby contact thereof with the pole pieces of the instrument is avoided.

The windings of the electro-magnets may be in series or in parallel, but in either arrangement a current of alternating or interrupted character will effectuate reversals in the polarity of the electro-magnets which are so wound as to alternately cause the armature to be attracted in opposite directions at its opposite ends upon the occurrence of a single impulse, and, at the same time, to be repelled in like manner. Combining these attractive and repellent forces, greatly improves the acoustical efficiency of the instrument, and also increases the sensitiveness in such degree that the electrical energy required to produce loud speaking, is very little.

The needle 8, Figure 6, is shown as applied to a slot 9 in which its tip rests, whereby it may move laterally and partake of the vibrations of the armature. The phonograph

would, in this instance, employ records having lateral undulations, but would be otherwise connected with the armature if another type of record were used. Figure 7 shows a hole 9^a, but a slot is preferable.

Having thus described my invention, what I claim is:

1. An electrical receiver including in combination a magnet, pole pieces for said magnet, an armature element disposed between said pole pieces, a continuous torsional spring, fixed at its ends, constituting a mounting for said armature element and of sufficient strength to normally retain said armature element in substantially a median position

between and to prevent its contact with said pole pieces, and windings for receiving current to cause said armature to be attracted and repelled by said magnet.

2. The combination with a magnet having proximate ends and provided with pairs of separated pole pieces mounted on said ends, an armature extending between said pole pieces, and a torsional spring mounting for said armature, said pole pieces being disposed within the physical limits of said magnet, and having contact with substantially the entire inner areas of said ends.

In testimony whereof I affix my signature.

HENRY M. WILLIAMSON.
